UNITED STATES PATENT OFFICE.

CHARLES F. BODINUS, OF AUSTIN, ILLINOIS.

CASH-CARRIER.

No. 906,486.

Specification of Letters Patent.

Patented Dec. 8, 1908.

Application filed March 2, 1907. Serial No. 360,144.

To all whom it may concern:

Be it known that I, CHARLES F. BODINUS, a citizen of the United States, and resident of Austin, county of Cook, and State of Illinois, have invented certain new and useful Improvements in Cash-Carriers, of which the following is a specification, and which are illustrated in the accompanying drawings, forming a part thereof.

10 The invention relates to cash carriers designed for use in pneumatic tube service, the carrier being preferably in the form of a cylindrical box adapted to be propelled through a tube by air blast.

15 The object of the invention is to simplify and improve the construction of devices of this kind; and the invention is exemplified in the structure to be hereinafter described and illustrated in the accompanying drawings, in which—

Figure 1 is a central longitudinal section of a cash carrier embodying the invention; Fig. 2 is an end elevation of the same; Fig. 3 is a sectional view taken on the line 3—3 25 of Fig. 1; Fig. 4 is a side elevation of one of the members of the carrier; Fig. 5 is a sectional view taken on the line 5—5 of Fig. 1; and Figs. 6 and 7 relate to details of construction.

30 The body of the carrier, as shown, is formed of two telescoping relatively-oscillatable members 10 and 11, each having an open end, as indicated at 12 and 13, the closed end of the inner member preferably taking 35 the form of a cap 14, the flange of which provides a shoulder 15 against which the open end 12 of the outer member may abut.

Each of the members 10 and 11 has a lateral opening, as 16, 17, respectively, such 40 openings being so placed that they may be brought into and out of register, to open or close the carrier, by the relative oscillation of its parts. The two members 10 and 11 are maintained in telescopic engagement by 45 means of interlocking circumferential ribs 18, 19, formed on the walls of the members, the wall of one of the members adjacent the rib being yielding in order that the parts of the carrier may be separated for repair, and 50 to lock the parts together means are provided for preventing the yielding of the wall of such member.

As shown the rib 19 is formed on the wall of the inner member 11 adjacent its open end 13, and the wall of that member is made

yielding adjacent the rib by continuing its lateral opening 17 to the open end of the member, as most clearly shown in Fig. 4. To lock the parts of the carrier in telescopic engagement, the yielding of the wall of the inner member is prevented when the parts are in assembled position by means of a flanged disk 20. This disk may be inserted, after the parts have been assembled, through the lateral opening in the carrier provided by turning the members 10 and 11 to bring the openings 16, 17, into register. It is held to its seat against the head of the outer member in a manner to be hereinafter described.

Cushions, as 21 and 22, are applied to 55 each end of the carrier, and as shown each of these cushions is secured in place upon the head of one of the members 10, 11, by means of bolts, as 23, 24, which enter the cushion from the chamber of the carrier, 60 through apertures in the head of the member. Preferably a plurality of bolts are employed for securing each of the cushions in place, in order that each cushion may be fixed against rotation on that part of the 65 carrier to which it is attached. As shown the bolts 23, 24, are tubular and are internally threaded. Preferably the bolts for securing each cushion have a common head 70 which takes the form of a plate 25 and serves 75 to reinforce the end of the carrier. Screws 26 engage each of the bolts 23, 24, and both of the screws for each of the cushions bear 80 upon a plate 27 which is countersunk in the outer end of the cushion. The bolts 23, 24, 85 at that end of the carrier adjacent the open end of the inner member 11, enter the cushion 22 through the head of the outer member 10 and through the flanged disk 20, for 90 the purpose of securing the latter in place. 95

The relative oscillation of the inner and outer members of the carrier is limited by a stop 28 applied to the inner wall of the outer member, the inner member being recessed to receive the stop and the ends 30, 31, of the 100 recess being adapted to engage the stop from opposite directions. As shown the stop 28 is applied to the wall of the outer member 10 adjacent its closed end, and the disk 20 is indented, as indicated at 29, (Fig. 7) 105 to provide room for the stop. Preferably the recess provided in the wall of the inner member for receiving the stop 28 is of such length that the two members of the carrier may be rotated from the open position shown 110

in Fig. 5 to the position shown in Fig. 3, the lateral openings 16, 17, being then out of register and the walls of each member of the carrier overlapping those of the other at 5 each side of the lateral opening for a sufficient amount to prevent the opening of the carrier by a slight relative rotation between its members.

In use the carrier may be opened or closed 10 if the end cushions 21, 22, be grasped and turned in opposite directions. The parts of the carrier may be disassembled for repair or inspection by loosening the screws 26 provided for securing the end cushions in place, 15 it being only necessary to permit the two body members of the carrier to be separated, to remove the screws 26 at that end of the carrier adjacent the open end 13 of the inner member 11.

20 The strength of the walls of the members 10, 11, of the carrier is increased by forming the lateral openings 16, 17, with angular corners, as indicated at 32, 33. The walls of the members are then less likely to be distorted 25 adjacent the corners of the opening when the rapidly moving carrier strikes an abutment, and the inclined corners serve by a cam action to bring the margins of the openings in the two members into proper relation to permit of the opening and closing 30 of the carrier when its walls have become slightly distorted.

I claim as my invention—

35 1. In a cash carrier, in combination, a pair of telescoping relatively oscillatable members having interlocking circumferential ribs, the walls of one of the members being yielding adjacent the rib formed thereon, and means for preventing the yielding 40 of the wall of such member.

45 2. In a cash carrier, in combination, a pair of telescoping relatively oscillatable members having interlocking circumferential ribs adjacent one end, the inner member having an open end and side adjacent the 50 rib, and a disk fitting the open end of the inner member.

55 3. In a cash carrier, in combination, a pair of telescoping relatively-oscillatable members having interlocking circumferential ribs adjacent one end, the inner member having an open end and side adjacent the rib, a disk fitting the open end of the inner member, and means for securing the disk to the head of the outer member.

60 4. In a cash carrier, in combination, an openable cylindrical casing, a cushion applied to the head of the casing, a plate applied to the inner face of the head, an internally-threaded tubular bolt projecting from the plate through the head and entering the

cushion, and a screw engaging the bolt and bearing on the cushion.

5. In a cash carrier, in combination, an openable cylindrical casing, a cushion applied to the head of the casing, a pair of internally-threaded bolts projecting outwardly through the end of the casing and into the cushion, such bolts having a common head, and a screw engaging each of the 65 bolts and bearing on the cushion.

6. In a cash carrier, in combination, a pair of telescoping relatively-oscillatable cylindrical members having interlocking circumferential ribs adjacent one end, the 75 inner member having an open end and side adjacent the rib, a plate fixed to the inner face of the end of the outer member and having a flange projecting into the open end of the inner member, and a fixed stop engageable by the margins of the open side of the inner member interposed between the flange of the plate and the cylindrical wall of the outer member.

7. In a cash carrier, in combination, a pair 85 of telescoping relatively-oscillatable cylindrical members, the inner member having an open side and end, a plate fixed to the inner face of the end of the outer member and having a flange projecting into the open 90 end of the inner member, the flange being indented to form a pocket, and a stop-block seated in the pocket and projecting into the space between the flange and the cylindrical wall of the outer member to be engaged by 95 the margins of the open side of the inner member to limit the relative oscillation of the two members.

8. In a cash carrier, in combination, a 100 pair of telescoping relatively-oscillatable cylindrical members having interlocking circumferential ribs adjacent one end, the inner member having an open end and a yielding side wall adjacent the rib, a plug fitting the open end of the inner member 105 and attaching means removable from without the outer member for securing the plug to the end of the outer member.

9. In a cash carrier, in combination, a 110 pair of telescoping relatively-oscillatable cylindrical members having interlocking circumferential ribs adjacent one end, the inner member having an open end and a yielding side wall adjacent the rib, and a plug fitting the open end of the inner member 115 detachably secured to the inner face of the end of the outer member.
